[57] CLAIM

The ornamental design for a wood splitter for use with a backhoe, as shown and described.

DESCRIPTION

FIG. 1 is a perspective view of the wood splitter for use with a backhoe embodying the design of the present invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom view thereof.

FIG. 1

FIG. 3

FIG. 2

FIG. 5

FIG. 4

FIG. 7

FIG. 6
